Patented Sept. 5, 1916.

Inventor

Robert E. Bolles

UNITED STATES PATENT OFFICE.

ROBERT E. BOLLES, OF NEW YORK, N. Y., ASSIGNOR TO FOWNES BROTHERS & CO., OF LONDON, ENGLAND, A FIRM COMPOSED OF WILLIAM GARDINER RIGDEN, WILLIAM FOWNES RIGDEN, EDWARD FOWNES RIGDEN, STANLEY FOWNES RIGDEN, HENRY URWICK, AND LESLIE ALAN SPALL.

DESIGN FOR A GLOVE.

49,600.

Specification for Design.

Patented Sept. 5, 1916.

Application filed June 6, 1916. Serial No. 102,096. Term of patent 3½ years.

To all whom it may concern:

Be it known that I, ROBERT E. BOLLES, a citizen of the United States, residing in the borough of Bronx, city of New York, county of Bronx, and State of New York, have invented a new, original, and ornamental Design for Gloves, of which the following is a specification, reference being had to the accompanying drawing, forming part thereof.

The drawing is a plan view of the glove showing my design.

Copies of this patent may be obtained for five cents each, by addressing the "Commissioner of Patents, Washington, D. C."

I claim:

The ornamental design for a glove substantially as shown.

In testimony whereof, I have hereunto subscribed my name.

ROBT. E. BOLLES.

Witnesses:

BESS BORDNER,
ELSIE VON QUITZOW.
